US0D1055024S

(12) **United States Design Patent** (10) Patent No.: **US D1,055,024 S**
(45) Date of Patent: ** Dec. 24, 2024

(54) **HEADPHONE BAND**

(71) Applicant: **Sonos, Inc.**, Santa Barbara, CA (US)

(72) Inventors: **Vincent Shyu**, Santa Barbara, CA (US);
Aki Laine, Santa Barbara, CA (US);
Dana Krieger, Santa Barbara, CA (US); **Philippe Vossel**, Wuppertal (DE)

(73) Assignee: **SONOS, INC.**, Goleta, CA (US)

(**) Term: **15 Years**

(21) Appl. No.: **29/926,153**

(22) Filed: **Jan. 29, 2024**

Related U.S. Application Data

(63) Continuation of application No. 29/869,395, filed on Dec. 29, 2022, now Pat. No. Des. 1,019,600, which is a continuation of application No. 29/864,135, filed on May 10, 2022, now Pat. No. Des. 974,327, which is a continuation of application No. 29/737,182, filed on Jun. 5, 2020, now Pat. No. Des. 954,019.
